DWIGHT F. KILGOUR, OF LEXINGTON, MASSACHUSETTS.

VALVE FOR SPRINKLER SYSTEMS.

1,288,918.

Specification of Letters Patent. Patented Dec. 24, 1918.

Application filed April 3, 1917. Serial No. 159,573.

To all whom it may concern:

Be it known that I, Dwight F. Kilgour, a citizen of the United States, and resident of Lexington, in the county of Middlesex 5 and Commonwealth of Massachusetts, have invented an Improvement in Valves for Sprinkler Systems, of which the following description, in connection with the accompanying drawings, is a specification, like 10 characters on the drawings representing like parts.

This invention pertains to improvements in valves for sprinkler systems and more particularly, though not exclusively, to 15 valves for so-called dry sprinkler systems provided with alarm mechanisms.

In the drawings:

Figure 1 is a section partly in elevation on the line 1—1 of Fig. 2;

20 Fig. 2 is a side elevation of a valve and is an illustrative embodiment of a preferred construction of my invention.

In the valve which I have selected for purposes of illustration, I have shown a cylinder 3, to which is connected a water supply pipe 4 and a discharge pipe 5, the latter being connected to the distributing pipes carrying the sprinkler heads. One end of the cylinder 3 is preferably closed by the 25 cylinder head 6, while the other end of the cylinder 3 preferably carries a head 7 having a small diameter cylinder 8 coaxial with the cylinder 3.

In the cylinder 3 I preferably provide, as 30 shown, a valve including two pistons 9 and 10 connected by a valve stem 11, the latter extending through the cylinder 8 and through a stuffing-box in the cylinder head 13 to a handle 14.

40 The valve stem 11 carries a piston 12 in the cylinder 8, the pistons 9—10—12 preferably being spaced apart by tubular spacers 14, 15 and the pistons and spacers being held in proper relation to the valve stem by 45 nuts 16—17.

A pipe 18, receiving pressure from any suitable pressure supply but preferably from the water supply pipe 4, is connected to the top of the cylinder 8.

50 Under normal conditions the valve remains in the position shown in Fig. 1, water under pressure being admitted between the pistons 9 and 10, which being of equal area are balanced. Water from the pipe 18 55 acting on the top of the piston 12 tends to move the valve downwardly to open posi-

tion, but the compressed air in the discharge pipe 5, though usually of much lower pressure than the water, acts on the lower end of the piston 10, to hold the valve plunger 60 in closed position as shown. If, however, the air pressure in the discharge pipe 15 be lowered by reason of the opening of a sprinkler head by fire or other cause, the water pressure on the top of the piston 12 will push 65 the valve down until the valve 40, the outcome of the operation of which is hereafter more fully described, is open, thereby admitting pressure to the top of the piston 9 and insuring outward movement of the piston 70 10 until it abuts on the cylinder head 6, leaving a substantially clear passage for the water from the supply pipe 4 to the discharge pipe 5. The relation of the discharge pipe 5 to cylinder head 7 and the piston 10 75 is preferably such that the piston 10 is substantially and entirely within the dead end 20 of the cylinder 3. To permit the escape of any water or air which may be caught in the cylinder end 20, I have provided a 80 round escape valve 21, having a slot 22 therein, and held in place by the friction of the packing in the stuffing-box 23. When the piston 10 is in the position shown in Fig. 1, the pressure of the air on the relatively small 85 area of the escape valve 21 is not sufficient to expel the escape valve from the cylinder. When, however, the nut 16 on the piston 10 strikes the end of the escape valve 21, the latter is pushed out of the cylinder, giving 90 an opportunity for the escape of air or water through the slot 22.

In the normal position of the valve shown in Fig. 1, no water pressure is admitted above the piston 9, and any water which may 95 leak past said piston has an opportunity to escape through the check-valve 24, which will not seat unless a considerable flow of water tries to pass therethrough.

The before-described mechanism constitutes a preferred form of unbalanced pressure fluid controlled dry sprinkler valve, and preferably co-operates with alarm mechanism of both the electric and pressure fluid actuated types. To this end I have shown an 100 arm 30 projecting from the handle 14 and connected by a rod 31 to the lever 32, fulcrumed at 33 on an arm 34 projecting from the cylinder 8. Carried by the lever 32 is an electric terminal 35 adapted to contact with 110 an electric terminal 36 carried by a sector 37 on the arm 34. The relation of the termi-

nals 35 and 36 is preferably such that contact will be made as soon as the piston 10 moves sufficiently to admit water to the discharge pipe 5. The water actuated alarm is 5 preferably actuated by water passing from the cylinder 3 through the cock 40, the latter being connected by the lever 41 and connecting rod 42 to the lever 32.

The valve 40 is preferably so arranged as 10 to open as soon as the upper side of piston 10 passes the upper side of discharge pipe 5, thereby admitting water to the latter. As soon as the valve or cock 40 opens, some of the pressure fluid passing therethrough goes 15 to the water alarm valve, while some of such water passes to the by-pass pipe 50, thereby admitting pressure to the top of the piston 9. Sufficient water passes through 20 the by-pass pipe 50 to cause the check-valve 24 to seat.

In the event that water-hammer occurs, the pistons 9 and 10 will have no tendency 25 to move the valve, because they balance each other. Water in the pipe 18 may transmit some variations in pressure to the piston 12, but such variation will be greatly lessened by reason of the relatively small size of the 30 pipe 18, and the increased pressure on the piston 12 will in any case be small because of the small area.

In case, however, the pressure from the water-hammer momentarily puts greater 35 pressure on the piston 12 than the compressed air puts on the piston 10, the reciprocatory positions of the valve mechanism may move toward discharge position, but the piston 10 does not move sufficiently to open the connection between the pipes 4 and 5, and the 40 air pressure will immediately return the piston to its initial position.

While I have shown and described one embodiment of my invention, it will be understood that changes involving omission, 45 substitution, alteration and reversal of parts, and even changes in the mode of operation, can be made without departing from the scope of my invention, which is best defined in the following claims.

Claims:

50 1. A valve for sprinkler systems comprising in combination a cylinder having an inlet conduit, and a discharge conduit, two connected pistons in said cylinder, one of

said pistons normally separating said inlet conduit from said discharge conduit, and the 55 other of said pistons normally balancing the water pressure on the first piston, and a third piston of lesser area connected to said two connected pistons and normally tending to shift said pistons to permit the flow of water 60 from said inlet conduit to said discharge conduit when the pressure in said discharge conduit is reduced.

2. A valve for sprinkler systems comprising in combination two coaxial cylinders 65 of different diameters, three connected pistons, two in the larger cylinder and one in the smaller cylinder, a water inlet conduit between said larger pistons, a discharge conduit containing fluid under pressure operating on one face of one of said larger pistons, and a conduit providing water pressure on 70 an opposing face of said smaller piston.

3. A valve for sprinkler systems comprising in combination a cylinder having a water 75 inlet conduit and a discharge conduit, a valve piston normally separating said inlet conduit from said discharge conduit, a second piston normally balancing the water pressure on said valve piston, and means 80 actuated by opening movement of said valve piston for admitting pressure fluid to the opposite side of said second piston to actuate further opening movement of said valve piston. 85

4. A sprinkler valve comprising in combination the cylinder 3, the inlet pipe 4, the discharge pipe 5, the piston 10 normally separating said pipes 4 and 5, the piston 9 normally balancing the water pressure on 90 said piston 10, and the cylinder 8 coaxial with said cylinder 3 and containing the piston 12, said piston 12 shifting said piston 10 on reduction of pressure in the pipe 5.

5. A sprinkler valve comprising in combination a water inlet conduit, a discharge conduit, valve means normally separating said conduits, valve shifting means for shifting said valve means on reduction of pressure in said discharge conduit, water 100 alarm means, and supplementary valve shifting means operative with initiation of operation of said water alarm means.

In testimony whereof, I have signed my name to this specification.

DWIGHT F. KILGOUR.
